CLAIM

The ornamental design for a heart-shaped baking pan lid, as shown and described.

DESCRIPTION

FIG. 1 is a top perspective view of the heart-shaped baking pan lid, showing the present design;

FIG. 2 is a top plan view of the present design;

FIG. 3 is a bottom plan view of the present design;

FIG. 4 is a left elevation view of the present design;

FIG. 5 is a right elevation view of the present design;

FIG. 6 is a rear elevation view of the present design; and

FIG. 7 is a front elevation view of the present design.

FIG. 8 is a top perspective view of the baking pan lid mated to a corresponding baking pan. The broken line showing of the baking pan is for illustrative purposes only and forms no part of the claimed design; and,

FIG. 9 is a bottom perspective view of the baking pan lid nested within a corresponding baking pan. The broken line showing of the baking pan is for illustrative purposes only and forms no part of the claimed design.
